UNITED STATES PATENT OFFICE.

NICHOLAS R. VARNEY, OF WALTHAM, MASSACHUSETTS.

STEM-WINDING WATCH.

SPECIFICATION forming part of Letters Patent No. 269,974, dated January 2, 1883.

Application filed October 25, 1882. (No model.)

To all whom it may concern:

Be it known that I, NICHOLAS R. VARNEY, of Waltham, in the county of Middlesex, of the State of Massachusetts, have invented a new and useful Improvement in Stem-Winding Watches; and I do hereby declare the same to be described in the following specification and represented in the accompanying drawings, of which—

10 Figure 1 is a top view of a watch with the dial removed. Fig. 2 is a top view, Fig. 3 a transverse section, and Fig. 4 a longitudinal section, of the stem and the mechanism thereof, of which I have invented to aid in effecting 15 either the "winding of the watch" or the setting of its minute-hand, the aforesaid figures being on an enlarged scale. Figs. 5, 6, 7, and 8 are hereinafter explained.

Heretofore in the manufacture of watches 20 the devices for moving the yoke in order to throw into gear that part of the stem-winding mechanism for effecting the setting of the minute-hand have been mostly, if not entirely, 25 in or applied to the pillar-plate and case of the time-piece, and not to the stem. Under such circumstances it has been found very difficult, if not impossible, with such devices and their mode of application to the case, to prevent 30 moisture or dust from working into the case through the aperture in which the device to be moved by the finger of a person extended.

In carrying out my improvement I have 35 within the stem and to extend from the yoke the mechanism for actuating the yoke so as to throw into gear the mechanism for setting the minute-hand. To this end I project from the yoke toward the stem an arm, and I have within 40 the stem a slide carrying a cam, which, when the slide is moved one way, or in, so acts against the arm as to press it aside in a manner to turn 45 the yoke to put in gear the hand-setting mechanism.

In the drawings, A denotes the case, B the pillar-plate, and C the stem, of a stem-winding 50 watch.

D is the yoke, which, as is well known, is a lever properly fulcrumed at its middle part, and having to each of its arms one of two spur-gears, a b, which engage with an intermediate gear, c, underneath the yoke. This gear c is usually coupled to a bevel-gear, d, which engages with a bevel-pinion, e, on the

winding-arbor f. A key, f', in the stem, and projecting from the winding crown or head g, fits upon the arbor f. On revolving the said 55 head g the gears of the yoke are put in operation.

Fastened to the pillar-plate is the spring h for moving the yoke to effect engagement of the gearing for winding the watch or its main-spring. The two gears to be engaged alternately with the gear of the arms of the yoke are shown at i and k, one of them being applied to the arbor of the mainspring and the other to a journal projecting from the pillar-plate. This latter gear engages with a pinion, l, on the arbor of the minute hand m.

My invention is to move the yoke so as to put the gear b into engagement with the gear k of the minute-hand-setting mechanism, and 70 also, as occasion may require, to enable the spring h to move the yoke so as to put the gear a in engagement with the gear i of the mainspring-arbor.

Within the upper part of the stem C is a 75 slide, n, which is adapted to move lengthwise in the stem in a dovetailed groove, o, made therein, this slide having on its outer surface a small projection, p, for the finger-nail of a person to bear against in order to move the 80 slide backward or forward within the groove. Leading down from the groove o there is in the stem a slot, q, which opens into the bore r of the stem. Within the said bore, and connected with the slide by a screw, s, is the cam t, shaped 85 as shown in top view in Fig. 5 and in edge view in Fig. 6. The inner end of the cam is beveled, as shown at u, and bears either against the end of an arm, v, extending from the yoke, at or near its middle, or against a suitable pin 90 or stud projecting from the arm. On the cam being moved in by the slide the beveled part u of said cam will move the arm so as to turn the yoke on its fulcrum to cause the gear b to be thrown into engagement with the gear k. 95 The crown or head g screws, as usual, upon the stem, and across the slide n are short sections w of screw-threads, corresponding in pitch to the screw-threads of the head and stem.

Fig. 7 is a top view, and Fig. 8 an edge view, 100 of the slide n, with its short sections w of screw-threads. On screwing the crown down upon the stem such crown will screw upon the sections w, and thereby prevent the slide from

being accidentally moved lengthwise. Before the slide can be moved the crown has to be sufficiently unscrewed on the stem.

I claim—

5 1. In combination with the arm projecting from the yoke, the slide and the cam, arranged in the stem, all being substantially as set forth.

2. The watch-case stem provided with the slide, and the cam connected therewith, and 10 slotted to receive the connecting-screw of the

slide and cam, all being substantially as set forth.

3. The slide provided with one or more sections of screw-threads, as described, to engage with the screw-threads of the crown, as and for the purpose set forth. 15

NICHOLAS R. VARNEY.
